UNITED STATES PATENT OFFICE.

WILLIAM W. PATTERSON, OF AUSTIN, MINNESOTA.

CARPET-STRETCHER.

SPECIFICATION forming part of Letters Patent No. 451,571, dated May 5, 1891.

Application filed June 11, 1890. Serial No. 355,039. (No model.)

To all whom it may concern:

Be it known that I, WILLIAM W. PATTERSON, a citizen of the United States, residing at Austin, in the county of Mower and State 5 of Minnesota, have invented certain new and useful Improvements in Carpet-Stretchers, of which the following is a specification, reference being had therein to the accompanying drawings.

10 My invention has for its object to provide a carpet-stretcher which is simple in construction, so that it may be cheaply manufactured, and which is powerful and efficient in action. To this end I provide a holding-bar which 15 has at its forward end a downturned prong and near its center an upwardly-extending projection, preferably consisting of flanges, between which is pivoted an operating-lever having near its fulcrum a pivotal connection 20 with arms extending rearward from a toothed stretching plate or jaw, the latter being provided with a loop embracing the forward end of the holding-bar and serving as a guide for the said stretching plate or jaw. The down- 25 turned prong or sharpened portion of the holding-bar is driven slightly into the floor when the carpet is to be stretched. The pivotal point of the operating-lever is of sufficient height above the body of the holding- 30 bar to permit the said lever to be turned down forward far enough to bring the pivotal connections of the arms therewith below the fulcrum of the said lever, so that when the 35 said lever is turned down forward it will be automatically locked, thus dispensing with the use of ratchet-bars and locking-pawl heretofore used in other devices of this character.

In the accompanying drawings, Figure 1 is 40 a perspective view of my improved carpet-stretcher. Fig. 2 is a side view thereof, showing the movable parts in different positions in full and dotted lines. Fig. 3 is a plan view of the stretching plate or jaw and its arms.

45 A denotes the holding-bar, provided at its forward end with a downturned prong a, the said holding-bar having near its center a raised projection consisting, preferably, of flanges b integral with the said bar. Between 50 the said flanges b, on a suitable bolt or pivot c, is pivoted the operating-lever B, having near

its fulcrum an offset portion or projection consisting, preferably, of the flanges b'.

C is the toothed stretching-jaw provided with two rearward-extended arms c', the extreme rear ends c² of which are turned sharply about at right angles to said arms and are extended through the flanges b' of the lever B, the said ends c² forming pivotal connections of the said arms with the said lever. 60

In practice my improved carpet-stretcher will be made of cast malleable iron, and will consist merely of three parts beside the bolt or pivot for the operating-lever. The flanges of the holding-bar and operating-lever are 65 formed integral therewith, and the arms c' of the stretching jaw or plate and the loop d on the latter are also formed integral with the said jaw or plate, the said loop serving as a guide for the said stretching-plate on the said 70 holding-bar. The upward projection on the holding-bar formed by the flanges b enables the fulcrum of the lever B to be raised high enough above the body of the said bar, so that when the said lever is turned down forward 75 to the position shown in full lines in Fig. 2 the pivotal connection of the arms c' with the said lever will be slightly below the lever-fulcrum, and when the said lever is thus turned forward it will be automatically locked 80 in this position, as the tension of the carpet on the teeth of the stretching-jaw will have a tendency to force the lever down as soon as it is turned forward far enough, so that said pivotal connection of the said arms with the 85 said lever comes slightly below the fulcrum of the latter. The ends c² of the arms c' are disconnected from each other, so that they may be entered into the apertures in the flanges b' merely by springing them apart 90 slightly, and as the said arms are preferably formed integral with the stretching-plate C it is obvious that this part of my device may be very cheaply constructed.

In the operation of my device the prong a 95 of the holding-bar A is driven slightly into the floor adjacent to the mop-board or position to be occupied by the edge of the carpet, and the operating-lever is then turned back as far as may be necessary to enable the teeth 100 of the holding jaw or plate to have any desired engagement with the carpet. The said

lever is then turned forward to the position denoted by full lines in Fig. 2, and when in such position, with the pivotal connections of the arms c' below the fulcrum-point c of the 5 said lever, the holding jaw or plate is automatically locked in position to hold the carpet stretched, as hereinbefore described. To bring the edge of the carpet up closely to the mop-board, the entire device should now be 10 swung laterally slightly in either direction on the pivot afforded by the prong a of the holding-bar, and thus one portion of the carpet held by the stretching-plate may first be brought up closely to the mop-board and tacked, and 15 then the stretching-plate be swung slightly laterally, and the other portion of the carpet held by said plate may be brought up to position.

From the foregoing it will be apparent that 20 my improved stretcher, consisting, as it does, of only three parts besides the pivot or bolt for the operating-lever, may be very cheaply constructed, while the relative arrangement of the parts shown and described provides a 25 device which is powerful in action and which will perform its work efficiently without danger of breakage.

I am aware that carpet-stretchers have heretofore been proposed somewhat similar to 30 mine, in that a stretching jaw or plate has been operated by a lever connected to a holding-frame, such as is shown by United States Patent No. 326,063, and I am also aware that it is not new to construct a carpet-stretcher 35 with a single holding-bar having a down-turned prong at its forward end and on which bar a stretching device actuated by an operating-lever is guided, such a device being shown by United States Patent No. 328,653; 40 but in the device shown by the former patent

there was no such relative arrangement of the fulcrum of the operating-lever to the pivotal connection of the arms of the stretching jaw or plate as would enable the latter to be automatically locked in its stretched position 45 without the use of pawls and ratchets, as is done in my device, and in the latter patent the stretching device was not so arranged as to engage the carpet close to its edge, and thus hold the edge firmly near where the 50 tacks were to be driven, as is done by my improved stretcher, in which the stretching-plate is forward of the fulcrum of the operating-lever and in close proximity to the prong 55 of the holding-bar.

Having thus described my invention, I claim and desire to secure by Letters Patent—

A carpet-stretcher consisting of the combination, with the holding-bar A , having the down-turned spur or prong a and the upwardly-extending flanges b , of the operating-lever B , pivoted between said flanges and having near 60 its fulcrum an offset portion or projection, and the toothed stretching-plate C , arranged forward of the fulcrum of the said lever and 65 near the said prong a , said plate being provided with the rearward-extending arms c' , converging toward each other and having at their rear ends the inturned portions c^2 , adjacent to each other, but adapted to be sprung 70 apart to be entered into openings provided therefor in the said flanges b , substantially as set forth.

In testimony whereof I affix my signature in presence of two witnesses.

WILLIAM W. PATTERSON.
